CLAIM

The ornamental design for a bracket for a sound processor and a coil, as shown and described.

DESCRIPTION

FIG. 1 is a perspective view of the bracket for a sound processor and a coil of the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is bottom view thereof; and,

FIG. 8 shows a perspective view of the bracket with a sound processor and a coil mounted on the bracket.

The broken lines in FIG. 8 are directed to environment and are for illustrative purposes only; the broken lines form no part of the claimed design.
